PHONOGRAPH

William H. Hutter, Chicago, Ill., assignor, by
mesne assignments, to Rock-Ola Manufacturing
Corporation, Chicago, Ill., a corporation
of Delaware

Application January 25, 1937, Serial No. 122,153

4 Claims. (Cl. 274—23)

This invention relates to improvements in phonographs and more particularly to improved mounting means for the playing arms thereof.

Multi-record phonographs of, for example, the selecting type, are employed in business establishments for the entertainment of guests. Under those conditions, they are frequently subjected to vibrations which are transmitted to the styluses or the needles of the machines and, therefrom through intervening mechanisms or circuits, to the sound amplifiers thereby impairing the quality of the reproduction. It is an object of the present invention to provide mounting means for playing arms of phonographs which, while affording the necessary horizontal swinging movement of the arms during the playing of the records and the pivotal movement of the arms to facilitate changing needles, insulates the arms from vibrations generated by the mechanisms of the machines as well as extraneous vibrations transmitted to the machines, and thereby avoid the transmission to the needle of such foreign vibrations as impair the quality of the reproduction.

Another object of the invention is to provide muting means, preferably carried by the playing arm, for preventing the reproduction of noises or sounds such as amplifier hums during intervals when no record is in playing position on the turntable.

Other objects of the invention relate to various features of construction and arrangement of parts which will be apparent from a consideration of the following specification and accompanying drawing wherein

Figure 1 is a perspective view of a multi-record phonograph, the present improved mounting means for the playing arms being embodied therein;

Figure 2 is an enlarged, broken, detached perspective view of a playing arm and associated improved mounting means;

Figure 3 is a vertical sectional view taken on line 3—3 of Figure 2; and

Figure 4 is a horizontal section taken on line 4—4 of Figure 3.

In the drawing, 10 indicates generally a multi-record phonograph of the record-selecting type and is provided with a turntable 11 for rotating the records during the playing thereof. In Figure 1 of the drawing a plurality of record carriers 12 are shown which, by suitably driven mechanism, are movable selectively to cooperate with the turntable in positioning their respective records in playing position. Machines of the

type mentioned generally are provided with coin control mechanism, such as is indicated at 13, and buttons or other selector control means 14 whereby a patron may deposit one or more coins and press a corresponding number of buttons 14 to effect the playing in succession of the selected records.

Disposed in operative position with respect to the turntable is a playing arm 15 shown in detail in Figure 2. The forward ends of the playing arms of machines of the type referred to generally are provided with means for converting mechanical vibrations imparted thereto by the needles or styluses into correlated electrical impulses which, after amplification, may be reproduced as sound by suitable means such as a speaker diagrammatically illustrated at 16. In Figure 2, conventional means 17 are indicated for converting the vibrations imparted by the record to the stylus or needle 18 into electrical impulses which, by means of suitable conductors 19, are transmitted to the amplifier of the machine, not shown. The playing arm 15 adjacent the rear end is so mounted that it swings horizontally to enable the stylus 18 to follow the sound grooves or tracks of the record being played and can also be moved about a horizontal pivot for a purpose to be more fully described presently.

The form of mounting means selected for the purpose of illustrating the invention comprises a 30 hollow spindle or shaft 20, to the upper end of which is attached a bracket 21 that is provided with opposite upstanding arms 22. In this embodiment of the invention, horizontally disposed pivot pins 23 are threadedly received in openings 35 in the arms 22 for adjustment with reference to retainer members 24 and may be releasably locked in an adjusted position by suitable means illustrated at 25 in Fig. 3. Interposed between each retaining member 24 and a side wall of playing 40 arm 15 is a vibration absorbing or insulating member 26. The insulating members are of any suitable cushioning material, such as rubber for example, and in the form shown are of block-like shape. The members 26 are seated at their 45 outer ends in the retainer members 24 and at their inner ends in cooperating retainer members 27, attached to or formed integrally with the vertical side walls of the playing arm 15.

The upper ends of the arm 22, as shown in Figs. 50 2 and 3, may be connected, if desirable, by a yoke 28 to support the upper ends of the arms against outward displacement as the pivot screws 23 are adjusted.

The members 26 are of such size that they ade- 55

quately sustain the playing arm, but being of cushioning or vibration absorbing material, they provide in effect a floating support which insulates the playing arm and needle from vibrations set up in, or transmitted to, the shaft 20 by the mechanism of the machine and such vibrations as may be imparted thereto from extraneous sources. The insulation of the playing arm from such vibrations, which would otherwise, to some extent, be imparted to the stylus 18 and thus detrimentally affect the record-imparted vibratory movements of the stylus, improves the quality of reproduction of the instrument.

Multi-record phonographs are frequently operated to reproduce a succession of records. During the changing of the records, the amplifier and speaker in such a phonograph remain energized for reproduction of sound as soon as the needle is engaged by the record to be played. In order "to mute" the pick-up device 17 and to prevent amplifier hum during the changing from one record to another or just prior to the playing of a record after the phonograph has been turned on, the bracket 21 is provided with a contact carrying member 29 carrying an electrical contact 30 which is electrically grounded to the bracket and hence to the phonograph chassis. Cooperating with that grounded contact 30 is an electrical contact 31 on a resilient contact carrying member 32 having a mounting flange 33 secured by suitable means 34 to the playing arm 15 and electrically insulated therefrom by suitable insulation 35. That contact carrying member 32 is electrically connected to one of the conductors 19 as shown at 36 in Fig. 2, and is operable by the playing arm 15 to move the contact 31 into engagement with the grounded contact 30 upon the completion of the playing of a record and to maintain the engagement until the next record is brought to playing engagement with the needle 18. Thus the pick-up device 17 is grounded or short-circuited during idle periods. As illustrated in Fig. 1, the turntable 11 is of the reciprocable type and in the playing position, the record on the turntable is brought up to engagement with the needle 18 and continues its upward movement to swing the playing arm 15 about the pivot pins 23 a distance sufficient to open the contacts 30 and 31. After playing, the turntable bearing the played record is lowered, whereupon the playing arm swings downwardly about its pivot pins 23 closing the contacts 30 and 31 to ground the pick-up until the next record is brought to playing engagement therewith. It will thus be seen that during the changing of records and other periods when the turntable with a record thereon is not in playing position, the pick-up device is grounded and thereby muted.

While I have disclosed an embodiment of my improvements for the purpose of illustration, it will be apparent that various changes of construction and arrangement of parts may be resorted to without departing from the spirit of the invention as defined by the appended claims.

I claim:

1. In a phonograph, a playing arm, mounting means therefor comprising a pair of supporting members disposed on opposite sides of said arm, a pair of socket members attached to said supporting members, a second pair of socket members attached to the sides of said arm adjacent said supporting members and spaced from said first pair of socket members, one pair of said socket members being pivotally mounted, and vibration insulating members each extending between and engaged at the ends thereof only by the respective socket members and being mutually capable of supporting said arm in operative position.

2. The combination with a playing arm of a phonograph, of horizontally swingable mounting means therefor, and means for securing said arm to said mounting means for pivotal movement with respect thereto comprising a pair of pivot members spaced laterally of said arm and resilient members of vibration absorbing material interposed between said arm and pivot members and secured at the ends thereof only to said arm and pivot members to provide a floating support for said arm.

3. Mounting means for a playing arm of a phonograph comprising a horizontally swingable member for supporting said arm, vibration insulating means interposed between said member and said arm to provide a cushion support for the latter, and means for attaching opposed portions of said insulating means to said arm and swingable member comprising spaced retainer members for said portions.

4. The combination with a playing arm of a phonograph comprising a member swingable on a vertical axis and having a pair of vertical supporting members spaced laterally of each side of a rear portion of said arm and means interposed between the sides of said arm and the respective vertical supporting members for pivotally attaching the arm to said supports for movement on a horizontal axis comprising a pair of vibration insulating members each provided with retainer members at the ends thereof, the retainer members of each insulating member being spaced apart by unconfined intermediate portions of the respective insulating members whereby the transmission of said vibrations from said supporting members to said arm are inhibited.

WILLIAM H. HUTTER.
